UNITED STATES PATENT OFFICE.

FRANÇOIS RICHARD, OF CLEVELAND, OHIO.

DESIGN FOR AN AUTOMOBILE-BODY.

50,799.

Specification for Design.

Patented May 15, 1917.

Application filed March 10, 1917. Serial No. 154,049. Term of patent 14 years.

To all whom it may concern:

Be it known that I, FRANÇOIS RICHARD, citizen of the French Republic, residing at 7800 Finney avenue, in the city of Cleveland, county of Cuyahoga, and State of Ohio, have invented a new, original, and ornamental Design for an Automobile-Body, of which the following is a specification, reference being had to the accompanying drawing, forming part thereof.

body embracing the features of my new design.

Fig. II is a side elevation of the same.

I claim:

The ornamental design for an automobile body as shown.

FRANÇOIS RICHARD.

Witnesses:

ANNA A. LUTTON,

CURT B. MUELLER.
